UNITED STATES PATENT OFFICE.

GEORGE C. LUCAS, OF CLEVELAND, OHIO.

RAILWAY-FROG.

No. 902,589.

Specification of Letters Patent.

Patented Nov. 3, 1908.

Application filed February 20, 1908. Serial No. 416,817.

To all whom it may concern:

Be it known that I, GEORGE C. LUCAS, a citizen of the United States, and a resident of the city of Cleveland, State of Ohio, have invented certain new and useful Improvements in Railway-Frogs, of which the following is a specification, accompanied by drawings.

My invention relates to a railway frog of that class in which the center portion or frog body, in order to withstand hard service, is made of some especially hard and tough material, such as manganese steel. This material, as is well known, cannot readily be shaped by ordinary tools, but must be ground by emery wheels.

One object of my invention is to produce a frog that shall be very durable in service and yet require little work of fitting, and this I attain by so shaping the center portion or body of the frog that it can be cast (or forged) into practically its finished form, and by so shaping those parts against which the rails fit that the rail ends will fit thereto with but little shaping. The invention further relates to the manner of combining the various parts of the frog, so that they will by mutual connection and interlocking form a self-contained practically unitary structure.

In the accompanying drawings, Figure 1 is a plan view of one form of frog; Fig. 2 is a plan view of the frog body; Fig. 3 is a sectional view on the line 3—3 looking towards the left. Fig. 4 is a sectional view on the line 4—4; Figs. 5, 6, 7, and 8 are sections of Fig. 1 on the lines 5, 6, 7, 8, respectively. Fig. 9 is a plan view of a modification. Fig. 10 is a cross section thereof on the plane 10—10. Fig. 11 shows in plan view the invention as applied to a double frog. Figs. 12 and 13 are cross sections on the lines 12 and 13 of Fig. 11.

The cross sections are on a larger scale than the plan views.

In the form illustrated in Figs. 1 to 8 a single point frog is shown in which the hard center or frog body is preferably a casting or forging of manganese steel or other suitable material of the form shown in Figs. 2, 3, and 4. Against this frog body the track rails and the two wing rails abut. The frog body fits the rails in such a manner that very little fitting of the rails is required.

The frog body B has a point 20 against which the two track rails C abut, and lateral raised portions or heads 21 against which abut at one end the two track rails D and at

the other end the wing rails E. Between the lateral heads 21 and the point 20 the grooves 23 to admit the flanges of the wheels are formed. The side faces of the body B are 60 channeled and contoured like the side of a rail, so that the abutting rails D and E which meet the heads 21 and are in alinement therewith, can be directly spliced thereto by means of the angle splice bars 30. It will be 65 seen that the lateral raised portions or heads 21 entirely interrupt and take the place of the rails D and E which abut and are alined with these portions. The frog body B forms, in fact, a complete frog entirely interrupting 70 the rails and replacing them with a hard durable frog body. Between the rails D the frog body is provided with a toe extension 24 which is fitted to the channels of the rails D, as shown in Fig. 8. Preferably a separate 75 filler block F may also be used.

At 25 inclines are shown for receiving the false flanges of the treads of worn wheels where the head portions 21 widen out from the rail D. At the other end the frog body 80 has a heel extension 26 which fits the channels of the rails C where they abut against the point 20. A filler block G may be added between the rails C where the angle is small, and filler blocks H may be fitted between the rails 85 E and C. In using the expression "rails" it will be understood that I mean also to include short pieces of rail such as the wing rail E. As shown in the section (Fig. 6) the frog body is fitted to the channels of the two 90 wing rails E at 28 near their ends.

It will be seen that where each of the track rails and wing rails meet the frog body, their ends abut against a raised portion which forms a continuation of the rail, while the 95 rail ends on one side receive portions of the frog body that fit into the channels of the rails similarly to filler blocks. Consequently the rails only require to be cut off squarely or at an angle, as the case may be, and secured 100 to the frog body. The sides of the raised heads 21 and of the frog body are contoured like the rails, as best seen in Figs. 4 and 7, having channels with overhanging heads and bottom flanges like the rails. Consequently 105 the splice bar 30, which is preferably an angle splice, as shown, can fit and be secured to the side of the frog body and to the rails D and E. Bolts are provided at frequent intervals, as shown, and serve to unite all the 110 parts into a structure which, by reason of the shape of the frog body, holds the rails very se-

curely to the frog body, giving very strong support against vertical as well as horizontal displacement of any of the parts.

Fig. 9 shows a single point frog of somewhat broader angle than Fig. 1. The point 20 has a heel extension 40 which comes up to the track level between the heads of the rails C and is tapered or inclined to receive the treads of the worn wheels, as will be well understood. At the other end, instead of one toe extension 24, two outside toe extensions 42 from the lateral raised heads 21 are shown which fit against and receive the outer sides of the converging rails D, and a bent or U-shaped splice bar J between the converging rail ends is bolted through the rails to the toe extensions 42. The toe extensions 42 should be tapered as at 43.

Fig. 11 shows the invention as applied to a two-point frog or center frog. In such frogs I may omit the lateral head portion 21 on one side over which the treads of the wheels do not pass, and employ a bent guard rail K. The two points 20 may be similar to either Fig. 1 or Fig. 2, and the angle being sufficient, I have shown them provided with projections 40, as in Fig. 2. In this structure the running rails are shown at L and M; the rails P are easer rails bolted to the rails M. The rails Q are guard rails which abut against the points 20 and fit the extensions 40. R are short rails slightly tapered to lead up to the raised lateral portion 21. The angle splice bar 31 is bolted to the contoured side of the raised or head portion 21 of the frog body and to the rails R and through the rails L, Q, M and K, some of the bolts extending through all these members. It will be seen that this construction shown in Figs. 11, 12 and 13, in common with the other forms shown, provides a frog body which entirely interrupts the track rails and takes their place, and is provided with a lateral raised portion or head 21, the side of which is contoured like a rail and secured to abutting rail ends by a splice bar.

I claim the following:

1. In combination in a railway frog, a solid frog body having one or more of its lateral sides of the same contour as a rail, and an angle splice bar fitting and secured to the said side of said body and extending the entire length of such side and projecting therefrom, one or more rails abutting against the body in line with the said side and secured thereto by said splice bar, and bolts securing the rails, frog body and splice bar together.

2. In combination in a railway frog, a solid frog body having head and point portions, four or more track rails abutting against the solid body, said body conforming and fitting the said track rails on one side and end of each rail, guard rails to which the said body similarly conforms, and splice bars and bolts securing the parts together.

3. In combination in a railway frog, a solid frog body having head and point portions, four track rail sections abutting against the solid body, said body conforming and fitting the said track rails on one side and end of each rail, guard rails to which the said body similarly conforms, said body having one or more head portions contoured like a rail on one side and a splice bar fitting thereto and to adjacent abutting rail portions, and bolts securing the parts together.

4. A railway frog, comprising a solid frog body having one or more outer side surfaces of the same contour as a rail, track and guard rails, and angle splices secured to the said side surfaces and connecting the body to the rails.

5. A frog structure, comprising a solid frog body having one or more outer side surfaces of the same contour as a rail, projections at each end of the body fitting between the rails, the track and guard rails, and angle splices secured to the sides of the frog body and connecting it to the rails.

6. A railway frog, comprising a frog body having a point, grooves and heads, guard rails abutting against the heads, track rails abutting against the heel and toe portions, and heel and toe filler projections of the said body fitting between converging track rails.

7. A railway frog, comprising a frog body having a point, grooves and heads, guard rails abutting against the heads, track rails abutting against heel and toe portions, heel and toe filler projections fitting between the converging track rails, and angle splices secured to the frog body and to the guard and track rails.

8. A railway frog, comprising a solid frog body, extensions on each end thereof fitting the rails, track and guard rails, filler blocks between the track and guard rails, and angle splices and through bolts securing the parts together.

9. In combination, a railway frog, a frog body, four track rail ends abutting on and secured to the body, said body having head portions against which all four of the said track rails abut throughout the width of their heads, guard rails, and splice bars fitting and bolted to the rails and to the side surfaces of the body.

10. In combination in a railway frog, a frog body, four track rail ends abutting on and secured to the body, said body having head portions against which all four of the said track rails abut throughout the width of their heads, and which conform to the rails on one side and end of each rail.

11. A railway frog comprising a frog body provided with grooves and head portions, rails, and a splice bar fitting the side of the said frog body and projecting therefrom, and bolts securing the splice bar to the frog body and extending through the splice bar

and through the webs of rails at either end of the bar, whereby the last said rails are connected by the bolts and splice bar to each other as well as to the frog body.

5 12. A railway frog comprising a solid frog body, track rails abutting against shoulders on each end of the body, guard rails abutting against other shoulders, extensions at each end which fit the track rails, and means for 10 securing the various parts together.

13. In combination in a railway frog, and with rails, a frog body having one or more points and heads, and contoured on one side like the rails, a splice bar secured to the said 15 side and projecting therefrom at each end, and rails abutting against the said body in alinement with the said side, and being secured thereto by the said splice bar.

14. In combination with rails, a frog body 20 having grooves and one or more points and at least one lateral raised head, the side of which is channeled like a rail, a rail abutting against and having its channel in line with the said channeled side, a splice bar secured 25 to the channeled side of the said frog body and to the last said rail, and bolts for securing the parts together.

15. A frog body having grooves and raised 30 portions for abutting rail ends and one or more end projections shaped to fit the sides of abutting rails, one of the lateral faces of

the said body being channeled and contoured similarly to a rail for receiving a splice bar and constituting means for securing a splice bar and abutting rail end with the side of 35 such abutting rail end against the fitting side of one of the said projections.

16. In combination with a rail end, a frog body having a head portion level with the head of the rail, in alinement with the head of 40 the rail on one side or gage line of the rail and of greater width than the said head, said head portion having an incline running down from the full height of the head for coöperation with the treads of worn wheels. 45

17. In combination with a rail end, a frog body having a head portion level with the head of the rail, in alinement with the head of the rail on one side or gage line of the rail and of greater width than the said head, said 50 head portion having an incline running down from the full height of the head for coöperation with the treads of worn wheels, said inclined portion being tapered or narrowed laterally toward the rail end, as at 25. 55

In testimony whereof I have signed this specification in the presence of two subscribing witnesses.

GEORGE C. LUCAS.
